COUPLING MEANS

Earl B. Parker, Athens, Pa., assignor to Ingersoll-Rand Company, New York, N.Y., a corporation of New Jersey

Filed May 8, 1962, Ser. No. 193,121

1 Claim. (Cl. 285-321)

This invention relates to a coupling means and, more particularly, to a guide sleeve for needle type descaling tools including coupling means for securing the guide sleeve in a plurality of preselected positions relative to the needles and housings of such tools.

In descaling tools having a plurality of needle like bits which are mounted for longitudinal reciprocation, it is desirable to provide a guide sleeve extending over part of the length of the needles to support and guide the distal end portions of the needles as they reciprocate. A guide sleeve is also desirable to shield the needles against accidental damage and to permit the operator to grasp the tool near the distal ends of the needles to achieve more accurate control of the tool.

Heretofore, as exemplified in U.S. Patent No. 2,672,677 to P. Von Arx, guide sleeves were not adjustable relative to the distal ends of the needles so that no change in the area of impact of the needle ends was possible except by substitution of different shaped guide sleeves or by providing the tool with two heads each having a set of needles and a fixed guide sleeve. This latter mentioned tool construction is undesirable since it provides a tool which is relatively complex and unwieldy and of limited usefulness in confined working space.

Accordingly, it is an object of the present invention to provide, in a needle type descaling tool, a guide sleeve which is adjustable relative to the needles of the tool.

Another object of this invention is to provide a guide sleeve for a needle type descaling tool which is of simple, inexpensive construction.

A further object of this invention is to provide a guide sleeve for a needle type descaling tool wherein adjustment of the guide sleeve relative to the needles of such tool can be achieved quickly and easily without the use of any tools or instruments.

A still further object of the present invention is to provide a guide sleeve for a needle type descaling tool which includes a simple and inexpensive means for locking the guide sleeve in a preselected position relative to the needles of the descaling tool.

A further object of this invention is to provide a simple and inexpensive coupling means for connecting a hollow member to another member wherein said hollow member surrounds the other member, and which means is capable of uncoupling the members without the aid of tools or instruments.

It is therefore contemplated by the present invention to provide a guide sleeve for a needle type descaling tool comprising a tubular member adapted to extend coaxially over the needle bits and capable of being axially moved relative to the needles and the housing of the tool. To secure the tubular member in one of a plurality of preselected positions to the tool, a locking means is provided. The locking means includes engaging means for engaging the tubular member and the housing of the tool to lock the tubular member in position to the tool. The engaging means is constructed and arranged so as to be disengageable from the tubular member and the tool housing without the aid of any tool or instrument.

The invention will be more fully understood from the following description when considered in connection with the accompanying drawing in which:

FIG. 1 is a view partly in section of a needle descaling tool having a guide sleeve according to this invention;

2

FIG. 2 is a section taken substantially along line 2-2 of FIG. 1;

FIG. 3 is a transverse sectional view taken substantially along line 3-3 of FIG. 1 showing the locking collar according to this invention in the locked position to secure the guide sleeve to the descaling tool;

FIG. 4 is a view similar to FIG. 3 showing the locking collar in the unlocked position to release the guide sleeve for movement relative to the descaling tool; and

FIG. 5 is a view in perspective of the locking collar.

Now referring to the drawing and more particularly to FIG. 1, the reference numeral 10 generally designates a needle type descaling tool of conventional construction. The descaling tool 10 comprises a housing, the forward end portion 12 of which is of reduced diameter and has an open end to receive the shank 13 of an anvil 14. In the rear portion of housing 11 is disposed a sleeve 15 which forms a piston cylinder in which a piston hammer 16 is disposed for reciprocation. A throttle valve (a part of which is shown projecting from the housing at 17) is disposed in the rear portion of housing 11 to control flow of fluid under pressure from a source thereof (not shown), such as a compressor, to the tool via supply hose 18. Actuation of the throttle valve is achieved by means of a lever 19 which is pivotally connected by pin 20 to housing 11. The tool is also provided with a conventional valve (not shown), such as a flapper valve, and conventional porting (not shown) to control flow of pressure fluid alternately to the front end and rear end of the piston cylinder so as to effect reciprocation of piston hammer 16.

Anvil 14 has a cup shaped end portion 21 which is integral with shank 13. A needle holder 22 is secured within end portion 21 by means of a snap ring 23 which maintains needle holder 22 in abutment against an internal annular shoulder 24 formed by a counterbored portion 25 in the end portion 21 of the anvil.

As shown in FIGS. 1 and 2, needle holder 22 is provided with a plurality of spaced bores 26 each of which bores is counterbored at 27. A needle type bit 28, having an enlarged head 29 at one end and tapered at the opposite end to provide a cutting edge 30, is disposed in each of the bores 26. The enlarged head 29 of needles 28 functions to prevent the needles 28 from passing through the bores 26 and thus out of engagement with needle holder 22. As shown in FIG. 1, the needle holder is mounted in spaced relationship to the bottom of cup-shaped end portion 21 so that a substantial space is provided within which each of the needles 28 is permitted to move axially relative to each other.

To secure anvil 14 within the forward end portion 12 of housing 11, a tool retainer assembly 31, such as is shown in U.S. Patent No. 2,854,238, is provided. The tool retainer assembly 31, as fully described in the aforementioned patent, briefly comprises a ball 32 which is retained in a socket or opening 33 in the end portion 12 of housing 11 by a sleeve 34. Sleeve 34 is secured to the housing end portion 12 by a snap ring 35. Sleeve 34 is provided with two spaced holes of different diameters, the smaller diameter hole being shown at 36 while the larger diameter hole, which is not shown, is of a diameter slightly larger than ball 32. The larger diameter hole serves, upon rotation of sleeve 34 into alignment with ball 32, to allow the ball to move out of the notch 37 in shank 13 of anvil 14 when it is desired to remove or insert anvil 14 in housing end portion 12 of the tool.

Interposed between sleeve 34 and the housing end portion 12 are two pairs of O-rings 38 which serve as shock absorbers. As shown, sleeve 34 is dimensioned in length so that it lies in close spaced relationship with an annular shoulder 39 formed in housing 11 by reduced end portion 12 so that an annular space 40 is

defined between the end of sleeve 34 and shoulder 39. The function of annular space 40 will hereinafter be explained.

In operation of the descaling tool 10, depression of lever 19 actuates the throttle valve, not shown, which valve permits pressurized fluid to flow into the piston cylinder thereby effecting reciprocation of hammer piston 16. On each forward stroke of hammer piston 16 it strikes the end of shank 13 of anvil 14 thereby imparting impacts to the latter which impacts, in turn, are transmitted to needles 28, and from the needles, to the surface being worked.

To provide a support and guide for needles 28 and to provide the operator of the tool with a means for grasping the tool as close to the ends of the needles as possible for more accurate control of the tool, a guide sleeve 41 is provided. As shown, guide sleeve 41 comprises an open ended tubular member 42 and a somewhat frusto-conical shaped end cap 43 secured to the forward end of tubular member 42. The internal diameter of tubular member 42 is slightly larger than the outside diameter of housing 11 so that tubular member 42 can be passed over the needles 28, anvil 14, and slidably engage housing 11.

For securing guide sleeve 41 in any one of a plurality of preselected positions, the tubular member 42 is provided with a plurality of longitudinally spaced arcuate slots 44 which cooperate with a locking collar 45 and annular space 40 as hereinafter more fully described.

As best shown in FIG. 5, locking collar 45 comprises a relatively thin walled open ended cylindrical member constructed of relatively resilient material and longitudinally split at 46. The inside diameter of the locking collar 45, in unstressed condition, is smaller than the outside diameter of tubular member 42 so that when it is slipped over the tubular member it is placed under tension. The collar is also provided with a tang 47 which lies in a plane perpendicular to its longitudinal axis and extends inwardly to the axis thereof.

As illustrated in FIGS. 1 and 3, tubular member 42 is slid upon housing 11 until one of the slots 44 is brought into register with annular space 40 to permit tang 47 of the locking collar to extend through a slot 44 into annular space 40 and thereby lock guide sleeve 41 in position to descaling tool 10. If it is desired to change the position of guide sleeve 41, locking collar 45 is rotated, in either direction, but preferably clockwise as shown in FIG. 4. The ends 48 of the edge of tang 47 of locking collar 45 are curved to provide a camming surface so that, upon rotation of the locking collar relative to tubular member 42, it readily rides out of slot 44 and thus out of annular space 40. With the locking collar 45 in the unlocked position, as shown in FIG. 4, tubular member 42 is free to be moved axially to another preselected position. When another slot 44 is brought into register with annular space 40, the locking collar is moved axially to bring tang 47 in alignment with the registered slot 44 and is then rotated, preferably counter clockwise, as viewed in FIG. 4, relative to tubular member 42 toward slot 44 and, since tang 47, 60 when riding on the surface of the tubular member places the collar under additional tension, the tang will snap into slot 44 and annular space 40. Thus, the guide sleeve 41 is locked to descaling tool 10 in another preselected position.

It can be readily seen from the foregoing description that a novel guide sleeve for a descaling tool has been provided which is simple and inexpensive and is capable of being adjusted relative to the tool in any one of a plurality of longitudinal positions without the aid of tools or instruments. It is a guide sleeve which permits the operator of the tool to exercise a high degree of control for each of a variety of working spaces.

Although the invention has been described as applied to a guide sleeve for a needle type descaling tool, it is to be understood that the invention need not be restricted thereto, but has application to connecting any hollow cylindrical member to another member wherein the hollow member surrounds the other member and quick and easy disconnection of the members is desirable.

Although but one embodiment of the invention has been illustrated and described in detail, it is to be expressly understood that the invention is not limited thereto. Various changes can be made in the arrangement of parts without departing from the spirit and scope of the invention as the same will now be understood by those skilled in the art. For example, an arcuate or annular groove may be provided in the outer surface of housing 11 into which tang 47 may extend in place of the annular space 40 formed between sleeve 34 and shoulder 39 of housing 11 without departing from the scope and spirit of this invention. It is also within the purview of the present invention to have the guide sleeve slidably within the housing and providing the housing with arcuate slots through which the tang of the locking collar may extend to engage a slot in the guide sleeve.

I claim:

Coupling means for connecting a hollow cylindrical member to another cylindrical member wherein said hollow cylindrical member surrounds said another cylindrical member, said coupling means comprising a slot in said hollow cylindrical member and a groove disposed in said another cylindrical member in register with said slot, and a split resilient ring disposed on said hollow cylindrical member for rotative movement relative to the latter, said split resilient ring having a relatively large width so as to be readily grasped by hand and having at one peripheral edge an inwardly projecting tang dimensioned to extend into said slot and said groove to lock said hollow cylindrical member and said another cylindrical member together, said tang having inclined end edges cooperating with the ends of said slot upon the rotation of said resilient ring to force said tang out of said slot and said groove and thereby disconnect said hollow cylindrical member and said another cylindrical member.
